Primary Examiner — Marissa J Cash(74) *Attorney, Agent, or Firm* — Steinfl + Bruno LLP(57) **CLAIM**

The ornamental design for a swept wing kite, as shown and described.

DESCRIPTION

FIG. 1 is a top perspective view of a swept wing kite showing my new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

In the drawings, the broken lines depict portions of a swept wing kite that form no part of the claimed design.
